CLAIM

The ornamental design for a trampoline with suspension members, as shown and described.

DESCRIPTION

FIG. 1 is a front perspective view of a trampoline with suspension members showing our new design;

FIG. 2 is a top plan view thereof;

FIG. 3 is a front elevation view thereof;

FIG. 4 is a bottom plan view thereof;

FIG. 5 is a rear elevation view thereof;

FIG. 6 is a right elevation view thereof; and,

FIG. 7 is a left elevation view thereof.

With respect to the drawings, stippled surface shading is used to represent a first appearance, line shading is used to represent a contrasting appearance, and alternating narrow line-bold line shading is used to represent another contrasting appearance for the suspension members.

The broken lines in the drawings represent unclaimed environmental subject matter and form no part of the claim.

1 Claim, 4 Drawing Sheets
